UNITED STATES PATENT OFFICE.

PAUL WINSOR, OF WESTON, MASSACHUSETTS.

REGISTERING APPARATUS.

No. 889,079.

Specification of Letters Patent.

Patented May 26, 1908.

Application filed March 15, 1907. Serial No. 362,467.

To all whom it may concern:

Be it known that I, PAUL WINSOR, a citizen of the United States, residing in Weston, in the county of Middlesex and State of 5 Massachusetts, have invented an Improvement in Registering Apparatus, of which the following description, in connection with the accompanying drawings, is a specification, like characters on the drawings representing like parts.

This invention relates to a registering or recording apparatus, such as now commonly used on street railways for registering the number of fares collected by the conductor.

15 The present invention has for its object to provide a register of the class described, with means, by which a record may be obtained of the number of fares registered by the conductor in a given time without such 20 record being known to the conductor, whereby the conductor is required to keep an accurate account of all the fares collected by him. For this purpose, the register is provided with a totalizer capable of indicating 25 a substantially large number of fares, with which coöperates a recording surface and means for printing or marking on said surface the numbers on the totalizer which register with said surface. The recording 30 surface is carried within a case or cylinder having a slot or opening to expose a portion of said surface, upon which exposed portion the conductor may write his name, date, car number, route number or any data desired. 35 The case or cylinder, which may be termed the record case, is designed to be placed in the register by the conductor at the beginning of his service on any car on which he may be employed during a given time, as for 40 instance, a day, and to be removed from said register by him at the termination of his services on the particular car. Provision is made for causing a record of the number indicated by the totalizer at the beginning of 45 the conductor's service and also at the end of such service, and provision is also made for removing such records from the view and knowledge of the conductor. Provision is further made for rendering the register 50 operative while the record case is accessible to the conductor, as will be described. These and other features of this invention will be

pointed out in the claims at the end of this specification.

Figure 1 represents in elevation and section a sufficient portion of a registering apparatus embodying this invention to enable it to be understood. Fig. 2, a plan view with parts in section of the apparatus shown in Fig. 1. Fig. 3, a vertical section on the line 3—3, Fig. 2. Fig. 4, a vertical section on the line 4—4, Fig. 2. Fig. 5, a detail to be referred to, and Figs. 6, 7, and 8 details to be referred to.

In the present instance, one construction 65 of apparatus embodying this invention is herein shown.

In the embodiment of the invention herein shown, *a* represents a fare register, which may be such as now commonly used on 70 street railway cars, and which is provided with a totalizer *b* of any suitable or usual construction and comprises as shown a plurality of wheels having numerals *c* on their peripheries. The totalizer *b* is operatively connected with the register proper, which connection is represented as a crank *d* and connecting rod *e*. The totalizer *b* is designed to be operated simultaneously with the register proper, which latter may be 80 operated in the usual manner by the conductor pulling a strap or turning a rod extended longitudinally of the car, or it may be operated in any other suitable manner.

The present invention has for its object to 85 provide a check on the conductor, whereby a record is obtained for the use of the officials of the railway system, of the number of fares registered by the conductor in a given time, which record is preferably unknown 90 to the conductor, and which compels the latter to keep an accurate cash account of his transactions and to make proper returns to the company. For this purpose, I employ a recording surface, preferably a strip 95 10 of paper (see Figs. 3, 6, and 7), which is placed upon a cylinder 12 inclosed within a case 13, preferably of metal and cylindrical in shape, so that the record cylinder 12 and its recording strip 10 may be readily inserted 100 into and removed from said case.

The record-holding case 13 with the record therein is designed to be under the sole control of the railway officials, and for this pur-

pose, said case may be provided with a door 14 at one end, which is adapted to be locked by a suitable device or seal 15, (see Fig. 6) after a fresh or clean record cylinder has 5 been placed therein.

To permit of access to the recording strip or surface 10 by the conductor, the case 13 is provided with a slot or opening 16 which exposes a sufficient area of the recording 10 surface to enable the conductor to write thereon his name and any other desired or required data, such for instance as the car number, route number, etc. In this manner the conductor is associated with his 15 record case or cylinder, and is prepared to assume charge of his car. In order to obtain means for checking the conductor, provision is made for printing or marking upon the portion of the recording surface exposed 20 by the slot 16, a number indicated by one row of numerals on the totalizer *b*, and further it is desirable that this record should be compulsory and not optional with the conductor. To this end, I have provided a 25 movable support for the record-containing case, which support is located within a chamber 17 formed by a casing 18 attached to or forming part of the case of the register *a*.

The movable support referred to, may be 30 made as herein shown and consists of a partial cylinder 20 having one end attached to the register case and its other or upper end free to move toward and from the totalizer (see Fig. 3), so that by moving the support 20 toward the totalizer, the number on 35 the totalizer in line with the exposed portion of the recording surface 10 may be printed upon said surface. This movement of the support for the record cylinder, 40 may be effected when the door 22 for the chamber 17 is closed, and in the present instance I have shown one construction of mechanism for accomplishing this result.

The mechanism referred to, consists of a 45 lever 23 pivotally attached to the door 22 and provided at its inner end with a stud or pin 24 (see Fig. 2) which extends into a curved slot 25 in a plate 26 attached to the top of the casing 18. The lever 23 is connected with the movable support 20 by a link 27. The slot 25 is shaped so that as the door 22 is closed, the movable support 20 and the record cylinder are moved forward, so as to bring the recording surface 55 and the ink ribbon 29 into engagement with the numerals of the totalizer in line with the slot 16 in the case 13, and as the door is opened a second printing is effected in the same manner. It will thus be seen that a 60 record is obtained of the numbers on the totalizer in line with the slot 16, when the conductor places his record cylinder in the register, and also of the numbers in line with the slot when the record cylinder is removed,

the difference between these two numbers 65 indicating the number of fares collected by the conductor while on the particular car.

Provision is made for preventing the register from being operated until the record cylinder is in its operative position and the 70 door 22 closed, and this result may be accomplished as herein shown by providing two locking devices for the totalizer, one of which is shown as a sliding rod 30 (see Fig. 8) extended through lugs 31 on the totalizer 75 frame 32 and provided at one end with a finger 33 which is adapted to be moved through a hole in one side frame and engage a tooth of a ratchet wheel 34 attached to the units wheel of the totalizer. The rod 30 has 80 connected to its opposite end a lever 35 having a finger 36 extended through a slot 37 in a gear 38 on the shaft of the record containing cylinder or case 13, said finger engaging the said cylinder when the latter is in its 85 operative position.

When the record case 13 is withdrawn from the support 20, a spring 40 moves the lever 35 so as to cause the locking finger 33 to engage the ratchet wheel 34 and thereby 90 lock the totalizer from being operated. The totalizer may also be held from movement by a second locking device under control of the door, and herein shown as a lever 41 having a finger 42 adapted to be held in engagement with the ratchet wheel by a spring 43 when the door 22 is open, and which is disengaged therefrom by the door engaging said lever when in its closed position as represented in Fig. 8. It is also desirable 100 that the conductor should not know the numbers of the totalizer printed on the recording surface, and for this purpose, provision is made for turning the record cylinder in its case, so as to cover the printed record. 105 To this end, the gear 38 has projecting from its center a device represented as a key 50 similar in appearance to a Yale lock key, and on which the case 13 and the record cylinder 12 are fitted, when a slot 51 in the end wall 110 of the case 13 registers with a slot 52 in the end wall of the record cylinder (see Fig. 3).

Referring to Fig. 3, the slot 51 in the case is substantially at right angles to the key 50, which is the position the key occupies after 115 the first impression is obtained and the record cylinder rotated so as to remove the printed record from in line with the slot 16. The record cylinder is rotated as herein shown by means of a shaft 55 (see Fig. 1) provided with 120 a gear 56 which meshes with a gear 57 in mesh with the gear 38, to the shaft of which latter the key 50 is attached. The gear 38 meshes with a pinion 59 (see Fig. 1) on a shaft 60 extended longitudinally of the case 125 18 and having arms 61, 62, which coöperate in turn with a lug or finger 63 on the inner side of the door 22 to lock the same. It will

thus be seen that after the record cylinder has been placed in the support 20 and an impression made by closing the door 22, the operator turns the shaft 55 so as to bring one 5 arm 61 behind the locking finger 63 to lock the door. The act of locking the door rotates the gear 38 and record cylinder 12 from the position represented by the slot 51 in Fig. 3 to that indicated by the key. This 10 movement of the record cylinder carries the printed record up under the case 13 and out of line with the slot 16, thereby concealing it from view. To unlock the door at the end of his work on the particular car, the operator turns the shaft 55 in the same direction 15 to remove the arm 61 from engagement with the locking lug or finger 63 on the door, and by so doing turns the record cylinder still further away from the slot 51 in the case 13. 20 The door is then opened by the conductor and a second printing is effected, and in order that this second record may be concealed from the conductor, provision is made for requiring movement of the case or cylinder 13 25 so as to cover the second printed record, before the case containing the record cylinder may be removed from the register. For this purpose the case 13 is provided with a lug or projection 66 on its outer surface which engages the free end of the support 20 and prevents the case 13 from being rotated in the same direction as the record cylinder, thereby 30 requiring the case 13 to be moved in the reverse direction so as to bring a second slot 35 67 in the end wall of the case into line with the key 50 in order to remove the record-containing-case from the register. This reverse movement of the case 13 causes the second printed record to be concealed from 40 view. Provision is also made to prevent the record cylinder 12 from being turned a complete circle in one direction, and to this end suitable stops are placed on the record cylinder and its inclosing case. 45 In operation with the apparatus herein shown, the conductor starting out on a car, receives a record case from the railway office. He writes his name and other required data 50 on the recording surface, and places the record case on its movable support. The door 22 is closed, and a record is obtained of the number on the totalizer. The door is then locked and the printed record removed from 55 in line with the slot 16. The register is at such time in condition to be operated to register the fares. At the end of the service of 60 the conductor on that particular car, he unlocks and opens the door which prints a second record on the recording surface, after which he removes the record cylinder from 65 the case, the second record in the meantime having been concealed from view. If the conductor's day's work is done, he turns his record case into the office, but if it is not, he starts on another car with the same record.

case, beginning all over again. At the end of his work for the day, the conductor turns his record case into the office, simultaneously with the fares collected by him, and the number of fares accounted for, should agree 70 with the difference between the numbers printed on the recording surface. Inasmuch as the conductor is ignorant of the number of fares registered, he is compelled to keep an accurate cash account and turn the same 75 into the office.

I have herein shown and described the printing on the recording surface as being effected as the door is closed and opened, but I do not desire to limit the invention in this 80 respect, as other mechanism may be employed to operate the recording surface and effect the printing otherwise than by the opening and closing of the door.

Claims.

1. In an apparatus of the class described, in combination, a register mechanism provided with a totalizer, a record cylinder provided with a recording surface, an inclosing case for said record cylinder provided with a 90 slot or opening to expose a portion of the recording surface, a support for said case movable toward and from said totalizer to effect a record on said surface, a door controlling access to said record-containing case, 95 means for connecting said door with said support to effect movement of the latter by movement of said door, means operated by said record-containing case for controlling the operation of said totalizer, means operated by said door for controlling the operation of said totalizer, and means for moving said recording surface while in the register to remove the record thereon out of line with the slot in its case, substantially as described. 100

2. In an apparatus of the class described, in combination, a register provided with a totalizer and with a chamber in line with said totalizer, a door for said chamber, a recording surface removable from said chamber, a 110 support for said recording surface movable toward and from said totalizer to mark a record on said surface, and means removable from said chamber with said recording surface and coöperating with the latter to conceal the said record from view, while the recording surface is in said chamber, substantially as described. 115

3. In an apparatus of the class described, a register provided within it with a totalizer, 120 a removable recording surface adapted to be placed within said register to coöperate with said totalizer, means for effecting a record on said surface of a number on said totalizer, and means removable with said recording 125 surface and coöperating therewith for concealing said record from the view of the operator while said recording surface is in said chamber, substantially as described.

4. In an apparatus of the class described, 130

- in combination, a register provided with a totalizer, a recording surface adapted to be placed within said register to coöperate with said totalizer and to be removed therefrom, 5 means for effecting a record on said surface of a number on said totalizer, and means for concealing said record from the view of operator while in said chamber, substantially as described.
- 10 5. In an apparatus of the class described, in combination, a register provided with a totalizer, a recording surface coöperating with said totalizer and removable from said register, means for effecting a record on said 15 surface of a number on said totalizer, and means removable with said recording surface and coöperating therewith to conceal said record from the view of the operator while said recording surface is in said register.
- 20 6. In an apparatus of the class described, in combination, a register provided with a totalizer, an inclosing case provided with a slot or opening in its circumference, a recording surface within said case having a portion 25 exposed by said slot, means for effecting a record on said surface of a number on said
- totalizer, and means for effecting relative movement of said recording surface and inclosing case to conceal the record on said surface, substantially as described. 30
7. In an apparatus of the class described, in combination, a fare register provided with a totalizer, a recording surface detachable from said register and coöperating with said totalizer to obtain a record on said surface of a number on said totalizer, and means removable from said register with said recording surface and coöperating therewith for concealing from view the record of the totalizer made on said surface while the latter is in 35 the register, whereby the said record is concealed from the view of the operator when the recording surface is removed from the register, substantially as described. 40
- In testimony whereof, I have signed my 45 name to this specification in the presence of two subscribing witnesses.

PAUL WINSOR.
